UNITED STATES PATENT OFFICE.

ARCH PIKE AND BERT PIKE, OF INDIANAPOLIS, INDIANA.

TIME SWITCH.

Application filed July 10, 1925. Serial No. 42,767.

Our invention relates to automatic switch controls, and more particularly to vehicle parking lights in which such lights are automatically turned on at a predetermined time of the day; and consists substantially in the construction, combination and arrangement of parts hereinafter set forth and pointed out more particularly in the claims.

An object of our invention is to provide a vehicle parking light switch which will automatically operate by clock control, the time for closing of such switch depending upon the time setting means of typical clock signal mechanism.

It is a primary object of our invention to adapt a standard signal clock mechanism, and a standard light switch mechanism for such purpose, in such manner as to have the automatic mechanism capable of being shifted entirely out of use whenever desired, leaving the switch mechanism unimpaired for ordinary manual manipulation, as originally intended.

It is also an object of our invention to provide an apparatus of this class which is widely adaptable to vehicle structures of different arrangement and dimensions, whereby the different parts need only be installed approximately correct as to working dimensions.

It is a further object of our invention to provide a spring operated switch of this class, the action of such spring depending upon a trigger releasing means which is in turn dependent for actuation upon a clock operated signal mechanism.

The above and other objects are attained by the structure illustrated in the accompanying drawings, in which Figure 1 is a fragmentary sectional plan view of our invention, different positions of the different parts being indicated by dotted lines, as will be understood; Fig. 2 is a fragmentary rear view; Fig. 3 is a sectional fragmentary end view taken in the proximity of line 3—3, Fig. 2; and Fig. 4 is a face view of the mechanism, the adjoining vehicle parts being only fragmentarily shown.

Similar characters of reference designate similar parts thruout the several views. Referring to Fig. 1, the numeral 1 designates a typical vehicle instrument board or dash, in which is contained the clock 2 of typical automobile size and arrangement. Said clock is secured to said instrument

board by means of the screws 3, which engage the concentrically arranged slots 4 of the clock face flange 5, each of which are large enough at the same respective end to slip over said screw heads, whereupon slight rotation of said clock as a whole will lock same on said instrument board.

Referring especially to Fig. 1 and Fig. 2, an alarm clock bell type beater 6 is shown embodied in said clock, which is, under certain conditions, adapted to strike the vertical extremity 7 of the trigger 8, upon which the operation of the mechanism depends, as will be understood. Said vertical extremity is preferably of somewhat long character, the pivoted portion 9 of said trigger being of horizontal disposition. Said trigger is pivoted to the horizontal plate 10 from which is downwardly formed a lower extending vertical plate 11, which is slidably held against the horizontally acting guide 12 by means of the stud 13 which engages said vertical plate, the horizontal slot 14 of said guide, and the corresponding slot 15 of the dash extension 16. The nut 17 of said stud is adapted to embrace the face of said extension near the clock 2, by which arrangement, shifting of the trigger 8 into and out of reach of the beater 6 may be carried out by using said nut as a shifting handle, as well as a means for retaining a correspondingly desired position of the plates 10 and 11 along the guide 12.

The parking light switch 18 is of typical "push-and-pull" design, having an exterior operating knob 19 which appears on the dash extension 16, and preferably on the other side of the clock 2 from the nut 17. Said knob is mounted on the outer end of the switch rod 20 which extends thru said dash extension, considerable distance interiorly, the inner portion of same engaging the guide bracket 21 in slidable relation. The switch brushes 22 of the switch 18 are interiorly mounted within an unexposed part of said extension. Said brushes are communicated with the parking light 23 and the source of electrical current 24, by means of the screws 25 and the conductors 26, as will be understood by those familiar with the art. A switch plug 27 formed on the rod 20 is adapted to be carried by said rod upon withdrawal of the knob 19, between said brushes into contact with same, by which the light circuit is closed, as will

also be understood by those familiar with the art.

The extreme inner portion of the rod 20 is provided with a longitudinally adjustable 5 collar 28, which is conveniently retained on said rod by means of the screw 29, said screw being threaded into said collar and into nosed contact with said rod.

Manual manipulation of the switch 18 is 10 carried out by means of the knob 19 and automatic manipulation is attained thru the collar 28 by means of the free end of the lever 30 which embraces said collar on the extreme inner surface of same. Said lever is pivoted 15 at its other end to the horizontal plate 10 and at a point between the ends, has a ledge 31 which faces the corresponding oppositely arranged ledge 32 formed on the trigger 8, the ledge 32 being arranged diametrically opposite on said trigger to its extremity 7. Said ledges are adapted, by contact with each other to normally restrain the action of the lever 30 against the collar 28.

Said ledges are normally held in contact 25 by the contractual coil spring 33 which engages the lever 30 and the guide 12, and tends constantly to swing said lever in the direction of the trigger 8 and the collar 28. By this arrangement, it is obvious that when 30 said trigger is rotated to a position indicated by the dot-and-dash lines 34, the ledge 32 will be correspondingly rotated out of alignment with the ledge 31 and the lever 30 will be oscillated by the spring 33, the plug 27 being correspondingly carried into contact with the brushes 22 by means of the rod 20 and the collar 28, which is actuated by the free end of said lever. It will therefore be understood that said trigger being thus actuated by 40 the beater 6 in accordance with the typical time signal setting hand 35 of the clock 2, will rotate the said trigger into the position 34, and by thus releasing the lever 30, close the switch, by which arrangement the automatic lighting of the parking light will take place at a predetermined time.

One end of the contractual coil spring 36 is secured to the horizontal plate 10 by the screw 37 on the opposite side of the trigger 8 from the clock 2, the other end being secured to said trigger by the screw 38, between the ledge 32 and the trigger pivot 39, by which arrangement said spring serves to 50 normally hold the vertical extremity 7 of said trigger, somewhat gently toward and in reach of the beater 6. A stop arm 40 is radially constructed on said trigger, however, which operates between the stop screw 41 and the stop bolt 42 of the horizontal plate 10, and serves to restrict the movements of said trigger, which prevents same from standing actually against said beater, although normally within reach of same. Said stop bolt is disposed thru the slot 43 of 55 the plate 10, by which arrangement the posi-

tion of same may be adjustably changed to establish the correct normal position of said trigger.

As before stated, the vertical plate 11 is 60 slidably secured to the guide 12 by means of the stud 13, said guide and the dash extension 16 having corresponding horizontal slots 14 and 15, respectively, for containing said stud, by which, lateral movement of same in said slots will correspondingly shift 65 said vertical plate horizontally on said guide. Said vertical plate is further supported on said guide by means of the screw 44, which slidably engages another slot 45 of said guide, co-directionally arranged with the slot 14, 70 said screw being threaded into said vertical plate, by which, movement of the stud 13 will impart to the screw 44 a corresponding movement in the slot 45, during the slidable action of said vertical plate on said guide. 75 The slot 45 is indicated by the dotted lines in Fig. 2.

When the stud 13 is laterally shifted in the 80 slots 14 and 15 to the position indicated by the dotted lines 46 of Fig. 1, by means of the nut 17, the horizontal plate 10 with the lever 30, the trigger 8 etc. are correspondingly shifted to a position indicated by the corresponding dotted lines. It will be obvious 85 that said trigger is then held considerably out of reach of the beater 6, making it impossible for the switch 18 to respond to the action of the clock 2, and the invention is further thrown out of use by having the lever 30 correspondingly withdrawn from the collar 28.

With this in mind, the free extremity of the lever 30 is constructed with prongs 47 which straddle the extreme protruding inner end of the rod 20, said prongs thus being 90 adapted to be withdrawn therefrom by horizontal movement of said lever, by using the nut 17 as a shifting handle, as before mentioned. In the opposite shifting movement, however, of said nut, in which said lever is 95 correspondingly moved into contact with the collar 28, it is necessary to have said prongs bent away from said collar as shown in Fig. 1, so that when said prongs are thus 100 moved into contact with said collar, they act 105 to cam themselves in sled-runner manner, onto the inner face of said collar.

The action of the beater 6 may be released or restrained as desired by means of the lever 48 which extends from the clock mechanism thru the concentric slot 49 of the clock 2, said lever having on and off positions as indicated by dotted and solid lines in Fig. 2, as in the case of ordinary bell ringing alarm clocks, and being related to 110 the clock mechanism in alarm clock manner.

The washer 50 is provided on the stud 13 and is adapted to embrace the inner surface of the dash extension 16, the shoulder 51 of 115 said stud being adapted to confine said wash-

er against said extension, so that tightening of the nut 17 tends to draw said washer up against said extension and cooperate with said nut in forming a locking means for locking said stud to desired positions along the slot 15.

The dash 1 comprises a standard automobile instrument board as part of standard automobile equipment, while the extension 16 is a section especially added to carry the guide 12, the switch 18, the nut 17, the vertical plate 11, etc., said extension being conveniently added on the lower edge of said dash and secured thereto by means of the screws 52. By this arrangement, it is very convenient to apply our invention to an ordinary automobile by furnishing said extension and its several carried parts as a unit, which may be assembled to the dash 1.

It is understood that such dash extension may be furnished in a variety of shapes to conform to dashes of different character. The clock 2 in many instances may be installed by replacing the standard automobile clock with same, which is especially constructed to form a separate unit of our invention. With this in mind the vertical extremity 7 of the trigger 8 is adapted to extend upwardly a considerable distance, making the dimensions between said clock and the extension 16 immaterial, as the ample length of said extremity will permit contact of same with said clock at any arbitrary height on the dash 1. This renders our invention easy to install on any vehicle dash which may have been previously constructed, without regard for our mechanism.

In applying the dash extension 16 to the dash 1, it is obvious that said extension may be located along the lower edge of said dash and shifted horizontally to a suitable relative position with the beater 6, which also makes our invention convenient to apply to any present vehicle dash, as a suitable location for same may be arbitrarily selected on same.

While we have illustrated in a general way, certain instrumentalities which may be employed in carrying our invention into effect, it is evident that many modifications may be made in the various details without departing from the scope of the appended claims, it being understood that our invention is not restricted to particular forms, herein described.

We claim as our invention:

1. An electrical switch mechanism comprising a plug type switch; a clock works having an alarm clock type beater; a lever, the free end of which is adapted to embrace and actuate the plug of said switch; a spring means tending to actuate said lever; a trigger means adapted to restrain said lever from actuation, said trigger means being disposed within working reach of said beat-

er, whereby said lever may be released to actuate said switch at a predetermined time, in accordance with the alarm setting means of said clock works; and an adjustable member on said plug for receiving the contact of said lever, whereby adjustment may be made of the working relation between said lever and said plug.

2. An electrical switch mechanism comprising a clock works having an alarm clock type beater; a lever, the free end of which is adapted to embrace and actuate the movable parts of the switch proper; a spring means tending to actuate said lever; a trigger means adapted to restrain said lever from actuation, said trigger means being disposed within reach of said beater, whereby said lever may be released by said trigger to actuate said switch at a predetermined time in accordance with the alarm setting means of said clock works; a journal member serving to pivot said lever and said trigger means, adapted to be moved for shifting said lever and trigger from and to said switch and said beater, respectively, to prevent or cause such actuation of said switch as desired; and an angular termination of said lever which serves to cam same onto working contact with said switch.

3. An electrical switch mechanism comprising a clock works having an alarm clock type beater; a lever, the free end of which is adapted to embrace and actuate the movable parts of the switch proper; a spring means tending to actuate said lever; a trigger means adapted to restrain said lever from actuation, said trigger means being disposed within reach of said beater, whereby said lever may be released by said trigger means to actuate said switch at a predetermined time, in accordance with the alarm setting means of said clock works; a member serving to pivot said lever adapted to be moved for shifting said lever from and toward said switch to prevent or cam such actuation of said switch as desired; and an angular formation on said lever serving to cam same onto working contact with said switch when shifted toward same.

4. An electrical switch mechanism comprising a clock works having an alarm clock type beater; a lever, the free end of which is adapted to embrace and actuate the movable parts of the switch proper; a spring means tending to actuate said lever; a trigger means adapted to restrain said lever from actuation, said trigger means being disposed within reach of said beater, whereby said lever may be released by said trigger to close said switch at a predetermined time, in accordance with the alarm setting means of said clock works; a member serving to pivot said lever and said trigger means, adapted to be moved for shifting said lever

and trigger means from said switch and said beater, respectively, to prevent such closing of said switch; and a handle secured to said member for manually performing such shifting.

5. An electrical switch mechanism comprising a clock works having an alarm clock type beater; a lever, the free end of which is adapted to embrace and actuate the movable parts of the switch proper; a spring means tending to actuate said lever; a trigger means adapted to restrain said lever from actuation, said trigger means being disposed within reach of said beater, whereby said lever may be released by said trigger means to close said switch at a predetermined time, in accordance with the alarm setting means of said clock works; a member serving to pivot said lever and said trigger means, adapted to be moved for shifting said lever and trigger means from said switch and said beater, respectively, to prevent such closing of said switch; and a means for locking said member in its different shifting positions.

6. An electrical switch mechanism comprising a clock works having an alarm clock type beater; a lever, the free end of which is adapted to embrace and actuate the movable parts of the switch proper; a spring means tending to actuate said lever; a trigger means adapted to restrain said lever from actuation, said trigger means being disposed within reach of said beater, whereby said lever may be released by said trigger to actuate said switch at a predetermined time in accordance with the alarm setting means of said clock works; a journal member serving to pivot said lever and said trigger means, adapted to be moved for shifting said lever and trigger means from and to said switch and said beater, respectively, to prevent or cause such actuation of said switch as desired; a face member serving to contain said clock works; and a guide means for said journal member adapted to be added to said face member as a continuation thereof.

7. An electrical switch mechanism comprising a clock works having an alarm clock type beater; a lever, the free end of which is adapted to embrace and actuate the movable parts of the switch proper; a spring

means tending to actuate said lever; a trigger means adapted to restrain said lever from actuation, said trigger means being disposed within reach of said beater, whereby said lever may be released by said trigger to actuate said switch at a predetermined time in accordance with the alarm setting means of said clock works; a journal member serving to pivot said lever and said trigger, adapted to be moved for shifting said lever and trigger means from and to said switch and said beater, respectively, to prevent or cause such actuation of said switch as desired; a face member serving to contain said clock; and a guide means for said journal member adapted to be added to said face member as a continuation thereof, said guide means being adapted to contain said switch and display a manual operating means therefor.

8. An electrical switch mechanism comprising a clock works having an alarm clock type beater; a lever, the free end of which is adapted to embrace and actuate the movable parts of the switch proper; a spring means tending to actuate said lever; a trigger means adapted to restrain said lever from actuation, said trigger means being disposed within reach of said beater, whereby said lever may be released by said trigger to actuate said switch at a predetermined time in accordance with the alarm setting means of said clock works; a journal member serving to pivot said lever and said trigger means, adapted to be moved for shifting said lever and trigger means from and to said switch and said beater, respectively, to prevent or cause such actuation of said switch as desired; a face member serving to contain said clock; and a guide means for said journal member adapted to be added to said face member as a continuation thereof, said guide means displaying a handle thru a clearance slot therein, said handle being secured to said journal member, whereby same may be shifted by said handle from the face of the mechanism.

In testimony whereof, we have hereunto set our hands on this the 1st day of July, 1925, A. D.

ARCH PIKE.
